CLAIM

The ornamental design for a combined cosmetic case and tray, as shown and described.

DESCRIPTION

FIG. 1 is a front view of a combined cosmetic case and tray showing our new design;

FIG. 2 is a rear view thereof;

FIG. 3 is a top plan view thereof;

FIG. 4 is a bottom plan view thereof;

FIG. 5 is a right side view thereof, the left side view being identical to the right side view;

FIG. 6 is a magnified cross sectional view taken along line 6—6 in FIG. 3;

FIG. 7 is a perspective view thereof; and,

FIG. 8 is a perspective view in a condition that a tray is drawn from the cosmetic case.
